N° 22032

Patented Nov. 9, 1858

UNITED STATES PATENT OFFICE.

HOSEA W. READ, OF WEST WINDSOR, VERMONT.

IMPROVEMENT IN HARVESTERS.

Specification forming part of Letters Patent No. **22,032**, dated November 9, 1858.

To all whom it may concern:

Be it known that I, HOSEA W. READ, of West Windsor, in the county of Windsor and State of Vermont, have invented an Improved Machine for Mowing Grass as well as for Reaping Grain; and I do hereby declare that the same is fully described and represented in the following specification and the accompanying drawings, of which—

Figure 1 is a plan or top view, Fig. 2 a side elevation, and Fig. 3 a longitudinal section, of said machine; Fig. 4, a transverse section of it, such being taken through its driving-wheels and axle. Fig. 5 is a top view of the cutters and their operating-slides.

The nature of my invention consists principally in a peculiar mechanism or application of mechanism for throwing the driving-pinions into or out of engagement with their driving-gears.

In carrying out my invention I employ a carriage, A, whose front end is supported by a shaft or axle, B, sustained by two driving-wheels, C D. The journals of the said shaft B extend beyond the carriage A or the boxes *a a* thereof and into boxes *b b* of a tilting frame, E, formed and arranged with respect to the carriage A, as shown in the drawings. The rear part of the said carriage is sustained by two swiveling wheels, F F, from the upper end of whose forks or holders G G two arms, H H, extend horizontally and parallel to one another and directly over a rack, I, arranged upon the platform K of the carriage. A slot, *e*, is made through each of the said arms, and receives a stud, *d*, which projects upward from a rack, I. Furthermore, a pinion, *e*, carried by a vertical shaft, *f*, works in the teeth of the rack, such shaft being arranged and having a hand-wheel applied to its upper part, as shown in the drawings.

The attendant or person who operates the machine is to stand on the platform K and in rear of the horse or animal by which the machine may be impelled forward, such animal being placed within the carriage A and in rear of the shaft B, and attached to a whiffletree, *h*, arranged below the shaft *f*, as shown in the drawings. When on the said platform K, the attendant, by laying hold of the hand-wheel and turning it horizontally, can easily cause the rear wheels to be swiveled or turned in a hori-

zontal plane into such an angle with the vertical longitudinal plane of the machine as circumstances may require, in order to change the direction of movement of the machine over the surface of the ground. He can also press downward upon the rear part of the tilting frame E, so as to tilt the same and raise the cutters off the ground or above the same to such extent as may be desirable. These cutters or knives, which are shown at *i i k k k*, are supported by the tilting frame or a cutter frame or holder, *l*, attached thereto. The said cutter frame or holder (an under side view of which is shown in Fig. 6) is furnished with a series of prongs or teeth projecting from it, which are surmounted by angular stationary cutters *m m*, &c. Each of the movable cutters *i* or *k* consists of a lever having the opposite edges of its front arm made to operate with two of the cutters *m m*. Furthermore, each lever-cutter *i* or *k* is arranged over and between two of the stationary cutters and turns on a vertical pin or fulcrum, *o*, and has its rear end or arm jointed to one of two slide-bars *p p'*, or otherwise so connected to the said bar as to be vibrated on its fulcrum *o* when the bar has a reciprocating rectilinear motion given to it. From the above it will be seen that there are two sets of cutters or cutting mechanism, each being operated separately from the other.

One of the driving-wheels C D, or that marked C, should be capable of rotating freely on the shaft B, the other of said wheels being fixed to the shaft. Thus the two wheels will revolve independently of one another in such manner that the revolutions of one may not be controlled by those of the other. Each wheel C D carries a bevel-gear or row of teeth, *q*, on its outer side, as shown in the drawings, each of the said bevel-gears being made to engage with one of two bevel-pinions, *r r*, fixed respectively to two secondary shafts, *s s*, supported by boxes *t t*, applied to the tilting frame, such shafts being arranged as shown in the drawings. Each shaft *s* carries a crank or crank-wheel, *u*, connected with one of the slide-bars *p* or *p'*, by a pitman, *v*. By such means each bar *p* or *p'* will have a reciprocating motion imparted to it when the driving-wheel next adjacent to it is in revolution.

A reel, R, may be arranged over the cutters in the ordinary way and rotated by an endless

band, *w*, working around two grooved pulleys, *x y*, one of which may be carried by the shaft of the reel, while the other may be fixed on the driving-shaft *B*.

In order to force the pinions *r r* out of engagement with the gears *q q*, a rod, 2, extends across the tilting frame and in front of the driving-wheel. This rod has a screw, *a'*, cut in it near one end of it, and made to screw into one of the bars *b' b'* of the tilting frame. The other end of the rod extends into the other bar *b*, and is provided with a shoulder, *c'*, to rest against the said bar or a bearer applied thereto. In the middle of the rod is a wheel, *d'*, or contrivance to enable the rod to be rotated. By revolving the rod on its axis the two bars of the tilting frame may be sprung apart from one another, so as to throw the pinions *r r* out of gear with their wheels, whereby, when the machine is moved over the surface of land, the action of the cutters may be arrested. By thus having the driving-wheels to rotate independently of each other, and by having two separate sets of cutters, each operated by a separate mechanism, put in operation by one of the driving-wheels, and the whole being arranged as shown in the drawings, I am enabled to gain important advantages, particularly while it is being turned about on the ground, in which case, as one driving-wheel will revolve faster than the other and is not controlled by it, the cutters of the former will operate much faster than those of the other, and thus there will be

no clogging of them, and the machine will be made to perform its duty with much better effect while being turned and with less labor for the horse than would be the case had it but one set of cutters, and those were operated by the two driving-wheels so fixed on or to the shaft that one could control the motion of the other.

In cutting grass or grain the machine is impelled forward by the horse, which, by being directly behind the cutters, is not subjected to the lateral twist or strain which results to a horse when the cutter-bar is made to project entirely on one side of the line of draft. Practice has demonstrated the great utility and advantage of my machine. When constructed of a proper working size a horse can readily step over the tilting frame and into or out of his place within the carriage.

I claim—

In its arrangement and combination with the tilting frame and the machinery for operating the cutters applied thereto, as described, a screw-rod or mechanism for spreading the bars of the tilting frame asunder, so as to throw the pinions of the cutter mechanism out of engagement with the gears of the driving-wheels, substantially in manner and for the purpose as specified.

HOSEA W. READ.
